REVERBERATORY FURNACE

Jack L. Stroman, Itasca, Ill., assignor to The
Petersen Oven Company, Chicago, Ill., a corpora-
tion of Illinois

Application May 18, 1948, Serial No. 27,800

1 Claim. (Cl. 263—33)

1

The present invention relates to reverberatory smelting furnaces. More particularly, the invention is directed to a novel furnace, preferably of the tiltable type, adapted for melting all types of ferrous and nonferrous metals and alloys, even alloys of high temperature type for casting below 3000 degrees F., as well as various ceramic type materials.

An object of the present invention is the provision of such a furnace having a novel form of combustion and melting chamber.

Another object of the invention is the provision of a furnace of this general class, in which there is no throat, such as is usually provided in such furnaces.

A further object is the provision of an improved smelting furnace, characterized by the provision of a chamber in the shape of a U, in which the bottom portion forms the combustion chamber and also serves to contain the molten material.

Another object is the provision of such a furnace in which the flame, for melting the metal, or other material being processed, is directed vertically downwardly onto the material.

A further object is the provision of a melting furnace in which the flame jets are so positioned with respect to the combustion chamber that the hottest part of the flame impinges on the metal or other material being processed.

A still further object is the provision of a furnace having a chamber of such a shape that the flame is caused to impinge on the metal in the combustion chamber and is deflected so as to sweep over the entire surface of the metal therein.

Another object is the provision of a metal melting furnace having an exhaust passage and which can be tilted to afford access therethrough for the operator for skimming off the slag from the molten bath, or for other operations.

Still another object is the provision of a novel type tilting furnace which can be tilted for washing the lining of the furnace for removing unmelted metal therefrom.

A further object is the provision of a novel type of tilting furnace which can be tilted for pouring the molten metal out through the exhaust passage if such should be found desirable.

A still further object is the provision of a furnace having a chamber in the shape of a U and having removable arches, in which when the arches are removed, the combustion chamber and the firing and exhaust passages have one side open and are readily accessible for relining, repairing, or replacing firebrick.

Other objects and advantages of this inven-

2

tion will be apparent from the following description, taken in connection with the accompanying drawings, in which:

Figure 1 is a perspective view of the metal melting furnace in a tilted position;

Figure 2 is an enlarged view from the front of the furnace, as viewed in Figure 1, but with the furnace in upright position;

Figure 3 is an end view, taken from the left of Figure 2;

Figure 4 is a plan view on a reduced scale, showing only the metal melting chamber with supporting frame and appliances removed;

Figure 5 is a sectional view taken on line 5—5 of Figure 4;

Figure 6 is a sectional view on a reduced scale taken on line 6—6 of Figure 4, but with the arch removed; and

Figure 7 is a side view of one of the sections making up the arch.

Referring now in detail to the drawings, the furnace of my invention includes a supporting frame indicated generally at 12, which is made up of a number of structural members welded or otherwise secured together. The frame is made up of end members 14 positioned in spaced apart relation and interconnected by other members, such as 16. At each end of the frame 12 are cradle rollers 18, which are journaled in brackets 20, secured to the upper surfaces of the end members 14 of the frame. The rollers 18 are arranged in pairs, the rollers of each pair being axially aligned and the pairs being positioned at the front and rear, respectively, of the frame. Each of the rollers 18 is provided with a lateral flange 22, the flanges of each pair being positioned on the outer sides axially of the rollers.

Supported on the frame 12, and particularly mounted in the cradle rollers 18, is the furnace proper, or melting chamber, indicated by the numeral 24. The melting chamber 24 is of a novel shape and construction and is generally in the shape of a U. The chamber 24 includes a bottom rounded portion 26 and two vertical portions, or legs, 28 at the front and 30 at the rear. The chamber is made up of a metal shell 32 having a portion 34 conforming to the outer surface of the U, and side wall portions 36. The shell is lined with firebrick 38 to the desired thickness, leaving a continuous channel or passage 40 having segments in each of the legs 28 and 30 and a curved segment in the bottom portion 26. The channel comprising the bottom portion 26 is, of course, rounded and is greater in depth than the width of the channels in either of the legs. The open side

of the channel faces inwardly of the U, that is, the segment in the bottom portion opens upwardly, and the segments in the legs have their open sides facing toward each other.

A number of arch sections 41 (Figures 1 and 7) are secured across the open side of the channel 40 formed in the melting chamber. Figure 7 shows the construction of the arch sections; these sections are included in the subject matter of my co-pending application, Serial No. 708,682, filed November 8, 1946, but for convenience a brief description of them will be given here. Each section 41 includes a top member 42 having a horizontal plate 43 and an upstanding rib 44. Adjacent the ends of the member 42 are end plates 46, secured to and extending downwardly from the underside of the plate 43. Reinforcing plates 48 are provided for strengthening the end plates 46. One end plate 46 is provided with a threaded hole for receiving lock screw 50, which is turned against locking plate 52. A plurality of fire brick 54 are positioned between the locking plate 52 and the end plate 46 at the opposite end of the arch section and held in place by the lock screw 50. When the series of fire brick are thus located and locked in the section, they form, in effect, a monolithic mass of fire brick. The brick are of greater transverse dimensions than the plates 43 and 46. The sections 41 are positioned across the open sides of the channel 40 formed in the melting chamber, and are of appropriate length to reach from end to end across the chamber. The shell 32 of the chamber is provided with appropriate flanges, such as 56, by means of which the sections 41 are secured in place. Figures 1 and 5 illustrate to best advantage the positions of the sections 41.

The arch sections 41, when in place—as above described—close the open sides of the channel 40 and close the melting chamber. The melting chamber thus includes a combustion chamber 58 at the bottom thereof and, as seen from Figure 5, has curved surfaces at the front and back, and a firing passage 60 and a combined exhaust and charging passage 62. The firing passage 60 and charging passage 62 are thus positioned adjacent the front and rear marginal edge, respectively, of the combustion chamber and are within the horizontal confines thereof. It will be observed that the firing and charging passages extend vertically upwardly from the combustion chamber in keeping with the fact that the chamber proper is of U shape formation.

Adjacent the top of the firing passage 60 are burner blocks 64, one of which may be supported in place by a ledge 66, imbedded in the fire brick 38, and the other one secured in place by resting on a ledge 67 on the firebrick of one of the arch sections 41, the firebrick thereabove having been offset to form the ledge. The burner blocks 64 form a restricted inlet 68 of minor depth at the upper end of the firing passage, but it will be noted that, except for the restricted inlet 68 the firing passage is otherwise of uniform dimensions throughout its vertical extent. The combined charging and exhaust passage 62 is also of uniform transverse dimensions throughout its vertical extent. As observed from Figures 1 and 4, the passages 60 and 62 are elongated, rectangular cross sectional dimensions with their long dimensions extending transversely across the furnace, or from end to end.

The combustion chamber 58 may be considered as having its upper limit adjacent the lower ends

of the passages 60 and 62, and it will be noted that there is no throat, or constriction, in either of the passages or in the combustion chamber itself.

5 A pouring spout, indicated generally at 70, is provided on the front of the furnace, adjacent the lower end of the leg 28, or at approximately the juncture between the combustion chamber 58 and the firing passage 60. The pouring spout 70 is formed by displacing outwardly a portion 72 of the shell 32 and securing side walls 74 thereto with fire brick. The spout is lined with firebrick for a portion of its extent, and completed with refractory material 76 which is molded in place over the firebrick, leaving an opening 78 communicating with the combustion chamber and opening out of the furnace. The outer extremity of the opening 78 is substantially at the level of the upper limit of the combustion chamber, or the juncture between the combustion chamber and the passages 60 and 62.

On each end of the furnace proper 24 is a bearing element 80 having an arcuate bearing surface 82. The bearing surface 82 is enclosed and strengthened by a metal plate 84. The end of the bearing member 80, adjacent the front of the furnace terminates a short distance above the bottom of the furnace, and the other end, which is adjacent the rear, or exhaust passage 62, is carried upwardly to a position adjacent the upper end of the furnace, or charging passage. A chain, or other flexible means 86 has its ends secured to the bearing member 80, adjacent the ends of the latter by means of clamps, such as 88. Each chain is disposed on the bearing surface 82 of the respective bearing members, but is of greater length circumferentially than the bearing surface and depends below the bottom of the arcuate bearing surface. The furnace proper 24 is supported on the frame 12 by means of the bearing members 80 resting in the cradle rollers 18.

45 Sprockets 90 are secured to a shaft 92 immediately below the respective arcuate bearing members. The shaft 92 is journaled in bearings, such as 94, spaced therealong and supported by the frame 12. The sprockets 90 are engaged by and in mesh with the respective chains 86.

At one end of the frame 12 is a housing 96 for 50 enclosing a drive motor and speed reduction means. The drive means may constitute an electric motor 98 and speed reducer 100 which are of conventional construction, interconnected by belt means 102. The gear reducer 100 includes a shaft 104 with a sprocket 106 thereon. A chain 108 is trained over the sprocket 106 and over another sprocket 110, secured on the shaft 92. The motor 98 is provided with the usual controls, including starting switches, limit switches, etc.

60 Positioned at the upper end of the passage 60 are a plurality of flame jets or burners 112, the number of which may vary according to the amount of heat desired and material to be melted. The burners 112 may be conventional mixer-burners and are arranged for directing flames directly downwardly into the firing passage 60. The burners are spaced along the long dimension of the firing passage and communicate with a fuel supply line 114, having a suitable connection with a source of fuel by means of a flexible hose. The burners may be mounted in any convenient manner in desired position and are connected to a manifold 116. The manifold 116 is connected 65 to the outlet of a blower 118, which is operated

by a suitable electric motor 120, or other means. The blower and motor are mounted on a platform 122, welded or otherwise suitably secured to the adjacent bearing member 80. The blower and motor are thus carried by the furnace proper. A convenient shield 124 may be mounted adjacent the burners 112 for shielding the flame.

A second pouring spout 70 may, if desired, be provided at the rear of the furnace, as indicated in dot dash lines at the left of Figure 5, similar to the pouring spout at the front of the furnace.

Use and operation

The furnace is charged with metal or other material to be melted through the combined exhaust and firing passage 62. The burners 112 are disposed for directing flame downwardly in the firing passage 60. The metal or material in falling through the charging passage 62 enters into the combustion chamber 58 and the flame on leaving the burners projects down into the combustion space and is deflected by the bottom of the combustion chamber and across the combustion chamber and then upwardly through the exhaust passage. All of the heat from the flame is directed onto the incoming material through the exhaust passage. When the material begins to melt and form a molten bath on the bottom of the combustion chamber, the flame impinges on the bath and is deflected thereby across the combustion chamber in the same manner, and then upwardly through the exhaust passage. The heated gases, on passing out of the exhaust passage, preheat the material being charged into the furnace and when the preheated material reaches the combustion chamber, it is more readily melted by the direct heat of the flame.

The furnace is adaptable for melting all types of ferrous and non-ferrous alloys, and other materials including those of the ceramic type, the number of burners 112 being determined by the amount of heat required for the particular material being melted. The burners 112 are distributed or spaced along the long transverse dimension of the firing passage 60 so that the heat from the flame is distributed evenly throughout the interior of the furnace. While the illustration herein shows two such burners, it will be understood, of course, that the number of burners can be varied. Because of the vertical arrangement of the firing passage, and the positioning of the burners at the top thereof, the flame possesses the greatest amount of heat in approximately the vicinity of the material being melted.

A novel feature of the present invention is that the flame impinges downwardly and into the vicinity of the pouring spout 70, and in the customary use of the device the spout 70 remains open and a portion of the flame is deflected outwardly through the pouring spout; in this manner, the walls of the pouring spout are retained heated so that they do not chill the molten metal when the metal is poured.

The U shape chamber of the reverberatory furnace is entirely novel. The chamber includes vertically disposed firing and exhaust passages communicating with the combustion chamber at the bottom, and the passages being within the vertical projection of the horizontal confines of the combustion chamber. An advantage of this type of furnace will be found from the above general description, namely that all of the flame and heated gases are deflected from the firing passage across all of the combustion chamber

and then out the combination exhaust and charging passage. None of the flame and heated gases can escape without first having come in contact with the material in the furnace. There are no throats or constrictions in the interior of the furnace.

By reason of the fact that the arch sections 41 can all be removed, the whole interior of the furnace can be made readily accessible for replacement, repair of fire brick, or for relining the furnace. When the arch sections are removed, the channel segments forming the firing and exhaust passages and the combustion chamber all have one side open and exposed so that workmen can easily gain access to the interior of the entire furnace.

The operation of the blower 118, in connection with the flame jets or burners 112, is believed to be readily apparent. On actuation of the blower, air is driven into the manifold 116 and then into the burners. This air produces an inspirator effect, drawing gas from the line 114 which is mixed with the air in the proper combustion proportions for the most efficient combustion of the fuel.

The furnace is readily adaptable to burning of other types of fuel besides gas, such as liquid, solid, solid pulverized fuel, or a combination of any of these.

30 The tilting operation of the furnace is brought about by means of the motor 98. The motor 98 is a reversible motor and is equipped with appropriate starting switches. When the motor is turned on and rotated in a given direction, the 35 drive is transmitted through the gear reducer 100 and through the chain 108 and sprocket 110. This rotates the shaft 92 which of course rotates the sprocket 90. The sprocket 90 on rotating clockwise (Figure 3) tilts the furnace 40 clockwise to the position illustrated in Figure 1 wherein the molten metal will discharge from the pouring spout 70. Rotation of the sprocket 90 in the opposite direction will tilt the furnace back to its normal upright position, illustrated in 45 Figure 3, and on continued rotation, the furnace can be tilted in the opposite direction from that illustrated in Figure 1.

If a spout 70 is provided at the rear of the furnace, the metal can be poured therethrough 50 on tilting of the furnace rearwardly the same extent as was done toward the front. However, if the spout is not provided at the rear, the furnace can be tilted a further extent to a position where the exhaust passage 62 slopes downwardly toward its normally upper end and the molten metal can be poured through the exhaust passage 62. For the latter purpose, the bearing member 86 is continued upwardly adjacent the exhaust passage a greater distance than on the 55 opposite side so that the furnace can be tilted rearwardly a greater extent. It will be understood that the bearing surfaces 82 on the opposite ends of the furnace move on the cradle rollers 13 and the furnace tilts on the axis of the arcs of 60 the bearing surfaces.

Another advantage of the rearward tilting of the furnace is that the exhaust passage can be accessible to a workman for skimming off any slag accumulation on the molten bath, or for stirring or puddling or for general observation.

Another advantage of the construction is that the furnace can be tilted rearwardly so that metal which tends to cling to the brick work, above the level of the molten bath, can be removed by immersing it in the bath. The bath

causes the clinging metal to melt and flow into the bath.

While I have herein shown and described a preferred embodiment of my invention, manifestly it is capable of modification and rearrangement of parts without departing from the spirit and scope thereof. I do not, therefore, wish to be understood as limiting this invention to the precise form herein disclosed, except as I may be so limited by the appended claim.

10

I claim as my invention:

A furnace of the character described, comprising, a refractory lined smelting chamber, said chamber being U-shape and having a bottom and upstanding legs, said bottom and legs 15 having channel segments therein forming a continuous channel, the open sides of the channel segments in said legs facing each other and the open side of the channel segment in said bottom facing upwardly, the inner edges of said legs 20 being disposed at an abrupt angle with respect to the upper edge of said bottom, removable refractory arch sections secured across the chan-

nel segment in said bottom and forming a combustion chamber therein, and removable refractory arch sections secured across the channel segments in said legs and forming passages therein, the latter arch sections being disposed in stacked relation on and above the former arch sections, one of said passages forming a firing passage and the other forming an exhaust passage.

JACK L. STROMAN.
